UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed November 21, 1921. Serial No. 516,607.

To all whom it may concern:

Be it known that I, WILLIAM F. HELMOND, a citizen of the United States, residing in Hartford, in the county of Hartford and 5 State of Connecticut, have invented certain new and useful Improvements in Typewriting Machines, of which the following is a specification.

In an Underwood typewriting machine, 10 the type-bar strikes a fixed abutment just as it reaches printing position, the point of contact with the abutment being between the ends of the type-bar. The type-bar springs against the platen with sufficient 15 force to make the desired impression, but cannot strike a second time, or make a double impression. This construction usually conduces to clearness and sharpness of the impression, and renders it permissible 20 for the type-bar to be made of considerable length and very thin and light.

In assembling the parts, it has been necessary to secure exactness of relationship between type-bars, the abutment or stop and 25 the platen, it being usually necessary for the type to be within less than five thousandths of an inch from the platen when arrested by the abutment, and it being also necessary to leave a space of some 30 thousandths of an inch between the type and the platen, so as to avoid blurring or double printing. The permissible variation in the position of the type when arrested by the abutment has therefore been microscopic, and difficult to secure. If the type-bar 35 strikes the abutment a trifle too soon, it results that the type-bar springs excessively in reaching the platen, and the extreme tip of the type therefore makes too heavy an impression, compared with the main 40 portion of the type. This ill effect is produced when the type-bar is not more than ten or fifteen thousandths of an inch away from the platen at the time it strikes the 45 abutment. The abutment is rather near the type end of the bar, causing the bar to spring or bend on a short radius, with the result that the top of the type prints so heavily. The effect is the same as if the type were 50 "off its feet," and the trouble has to be corrected by bending the type-bar with tools, or by fitting the type-bar more closely with relation to the abutment. This is a slow and expensive operation, every type-bar hav-

ing to be carefully tested for exactness of 55 relation with abutment and platen.

The lateral vibration of the type-bar is considerable, tending to impair the side alignment and the spacing of the type impressions. The capital letters particularly 60 tend to incline to the right or left when the machine is rapidly operated, the axis of the lateral vibration being at about the point where the type-bar strikes the abutment, which, as already noted, is rather near the 65 type, so that the angular extent of the lateral vibration is considerable.

In overcoming these difficulties, each type-bar is provided with a tongue or device projecting therefrom which strikes the abutment 70 or stop just as the type almost reaches the platen. Said tongue is preferably resilient, and integral with the type-bar. In using this improved bar, the types can be from five thousandths to fifteen thousandths of 75 an inch from the platen when the yielding tongue or buffer contacts with the abutment. The improvement renders close work unnecessary, there being such a large margin that a high degree of skill is not required 80 for adjustment, and the machine can be manufactured more cheaply and rapidly.

After the abutment is struck, the improved bar can yield for a distance that is about equivalent to the entire length of the 85 bar. Owing to this great springing or bending length, the type prints evenly. The difficulty of the top of the type printing the heaviest is overcome. The improved bar can be as far as fifteen thousandths of 90 an inch away from the platen, when it is arrested by the abutment, without printing heavily at the top of the type. This affords considerable advantage in lowering the cost and expediting the work of alignment, since 95 a lower grade of aligning skill can be engaged, microscopic closeness of relationship of the parts not being required, and it being therefore unnecessary to give the usual close attention to testing the type-bars with 100 relation to abutment and platen, a substantial range of variation being permissible.

A further advantage of the improved type-bar is that noise is reduced because the part that strikes the fixed abutment is 105 yielding.

The yielding tongue is springy and pulls back the type instantly from the platen,

eliminating liability to blur. Moreover, since the type-bar starts back more promptly from printing position to its normal position, high speed of operation is favored.

5 Better carbon copies are produced, because the type-bar is not stopped so sharply by the abutment, and does not have to bend or spring so much locally as heretofore. The invention has the effect of stopping the type-bar just the way it should be stopped.

10 In the new type-bar, the lateral vibration does not center at the point of contact with the abutment, as heretofore, but centers at a point close to the pivot of the type-bar, this being due to the use of the spring tongue. The tremor takes place near the root of said tongue, and the lateral vibration of the types is reduced, because the type-bar is very closely supported on both 15 sides by the segment at about the axis of the lateral vibration. The type impressions therefore have better side alignment, and the impressions of the capital types also stand straighter, especially in rapid operation. The type impressions do not flare out to the right or left, and they stand in better vertical alignment. There is a sharper blow of the type on the paper.

20 Other features and advantages will hereinafter appear.

25 The accompanying drawing shows a type-bar in normal position, and one as it strikes the abutment.

30 The type-bars 1 are pivoted on a fulcrum-wire 2, and are operated by key-driver levers 3. The wire 2 is mounted in a segment 4, which has radial guide-slots 5 for the type-bars; said segment being provided with a dust-shelf 6 over the slots. The type 35 strikes rearwardly against a platen 7. A carriage-feeding universal bar 8 is operated by the type-bars. Each type-bar is a plate of thin sheet-metal having a longitudinal stiffening rib 9.

40 Extending upwardly from the base portion of the type-bar, towards the free end thereof, is a tongue 10, to contact with an abutment 11 on the front face of the segment 4, this abutment being of arc shape, suitable for all the type-bars. The spring 45 tongue may be formed by cutting a long kerf or slot 12 at the middle of the bar, at a widened portion thereof, said widened portion beginning at 13 just above the dust-shelf 6. The tongue 10 may be of any required length, the arc of the abutment being made of smaller radius where the tongue is longer.

50 When the tongue strikes the abutment, there is springing action, beginning at the abutment and extending down through the tongue and then up along the type-bar to the type; the tongue and type-bar both having a springy construction. This gives a length 55 of spring which is about equivalent to the

entire length of the type-bar, and the type can spring very much more than heretofore after the type-bar strikes the abutment, and there is more uniformity of type impression, and less need of securing the precise relation 70 heretofore found necessary between the type, the platen and the abutment.

75 The abutment 11 is barely raised from the front surface of the segment. This permits the axis of the middle body-portion of the type-bar to be more nearly coincident with a line drawn from the pivot to the type, thus tending to reduce liability of skewing and distortion of the type-bar at the moment of printing. The slotted portion of the segment projects far forwardly from the face of the segment, and the standing type-bar at its bottom portion bends in close to the front face of the segment, and keeps this close relationship for the rest of 85 the distance to the type.

80 Variations may be resorted to within the scope of the invention, and portions of the improvements may be used without others.

Having thus described my invention, I claim:

1. The combination with a platen, of a pivoted type-bar to print against said platen, a type-bar stop device, and a tongue integral with said type-bar to engage said stop device before the type touches the platen, said tongue joining the type-bar near its pivot portion and extending towards its type end. 95

2. The combination with a platen, of a type-bar to print against said platen, said type-bar having a longitudinal kerf, a tongue formed by said kerf, and a type-bar stop to be engaged by said tongue just before the type-bar engages the platen. 100

3. The combination with a platen, of a plurality of radially-arranged pivoted type-bars, means to guide the types laterally at their pivots, a type-bar guide to be engaged by the free ends of all the type-bars, a type-bar stop device about midway between the pivots of the type-bars and the type-bar guide, and a resilient tongue on each type-bar to engage said stop device, the tongues joining the type-bars in proximity to said lateral guiding means. 110

4. The combination with a platen, of a plurality of radially-arranged pivoted type-bars, a type-bar segment having radial slots for the type-bars, a guide at the printing point, and a stop face on said segment, each type-bar having a tongue to engage the stop face before the type-bar touches the platen, the tongues being connected to their respective type-bars near the slots in the segment and extending along the bars toward their type ends. 120

5. The combination with a platen and a radially-slotted segment having a stop device in the form of a rib barely raised from the surface of the segment, of a series of piv- 125

oted type-bars working in the slots, and types to project rearwardly from the type-bars to strike the platen, the slots having a dust guard at their upper ends, and the type-bars formed with cutaways to enable them to clear the dust guard and reach said stop rib when in printing positions, each type-bar having a longitudinal kerf extending from about its middle portion towards the pivot 10 end of the bar, said kerf forming a tongue which engages said stop rib just before the type strikes the platen.

6. A pivoted type-bar formed of thin metal and having near its pivot portion an 15 integral tongue extending towards its free end, and a stop to be engaged by the free end of the tongue just before the type strikes

the platen, the type-bar and the tongue being both resilient, to permit the type to spring to the platen after such arrest.

7. The combination with a radially-slotted segment having a stop device in the form of a rib raised from the surface of the segment, of a series of pivoted type-bars working in the slots, each type-bar having a longitudinal kerf extending from about its middle portion towards the pivot end of the bar, said kerf forming a tongue which engages said stop rib just before the type strikes the platen.

WILLIAM F. HELMOND.
